HEAD LAMP

Clarence A. Michel, Howard C. Mead, and Robert Winkelmeier, Anderson, Ind., assignors to General Motors Corporation, Detroit, Mich., a corporation of Delaware

Application February 12, 1936, Serial No. 63,500

6 Claims. (Cl. 240—41.6)

This invention relates broadly to illuminating apparatus and more specifically to headlamp structure for purposes of illuminating the highway in front of a moving vehicle.

5 It has heretofore been the general practice to mount the headlamp casing of a car so that the same may be moved with respect to the body or frame of the vehicle for purposes of aiming the beam in the proper driving position. However, it has been found advantageous both from the standpoint of assembly and maintaining the proper adjustment to rigidly secure the headlamp outer casing to the body or frame.

10 It is therefore an object of our invention to provide a headlamp having a plurality of casings, one within the other, the outer casing to be attached to the body and the inner for adjustment purposes.

15 It is a further object of our invention to provide a headlamp in which all the necessary adjustments for aiming are self-contained.

It is a still further object to provide a headlamp in which the self-contained adjustments are accessible from outside of the headlamp.

20 For a better understanding of the nature and objects of our invention, reference is hereby made to the following specification wherein there are described the embodiments of our invention which are illustrated in the accompanying drawings, in which:

Fig. 1 is a longitudinal plan of a headlamp of our invention, parts being broken away and shown in section.

25 Fig. 1a is a section through the side portion of the headlamp showing modified means for adjusting the beam horizontally.

Fig. 2 is a sectional view taken on the line 2—2 of Fig. 1.

30 Fig. 3 is a front view of the headlamp with the lens and its supporting ring removed.

Fig. 4 is an enlarged detail sectional view taken on the line 4—4 of Fig. 2.

35 Figs. 5 and 6 are enlarged sectional views taken on the lines 5—5 and 6—6 of Fig. 1.

40 Fig. 7 is a detail perspective view of a reflector retainer.

Fig. 8 is a detail perspective view of the spring clip for tilting the reflector.

45 Fig. 9 is a front view of the inner casing.

50 Fig. 10 is a horizontal section taken through a headlamp and showing a modified form of our invention.

Fig. 11 is an enlarged partial sectional view 55 taken on the line 11—11 of Fig. 10.

Fig. 12 is a partial front view with parts broken away and shown in section.

Fig. 13 is a sectional view taken on the line 13—13 of Fig. 12.

Fig. 14 is a similar view to that of Fig. 11 showing a further modified form of the invention.

Referring first to the form of invention illustrated by Figs. 1—9, a thin sheet metal lamp body 2 has a heavy reinforcing plate 4 of the same configuration supported against the inside surface of the body. Adjacent each end of the reinforcing plate 4 there are openings 6 within which are secured suitable nut supporting and locking members 8 to support nuts 10 and keep the same from turning. The body 2 has openings 12 therein in alignment with the nuts 10 for securing purposes.

A mounting bracket comprising parts 14 and 16 at the front and rear respectively is secured to the body by bolts 18 threaded into the interior nuts 10 and having heads 20 on their outer ends. The bracket portions 14 and 16 both have attaching bolts 22 cast therein which are adapted to project through the member upon which the lamp is to be mounted, in this case the radiator shell 24 and the inner reinforcing plate 26. Nuts 28 hold the assembly in place by being threaded on the bolts 22.

The body 2 is of streamline or teardrop shape with the front thereof open and the body being flanged inwardly as at 30 around the opening. Fitting within the open end of the body 2 is a sub-body 32 which is circular, the outer portion dished inwardly and the periphery being flanged outwardly and then forwardly as at 34. Secured to the outwardly flanged section of the sub-body at spaced peripheral points are a plurality of attaching pins 36 having a small body and an enlarged head 38. In the flange 30 at points 40 adjacent the pin positions of the sub-body there are provided openings 40 of irregular shape, one end being enlarged and round and the remainder being an elongated slot. Projecting behind these openings 40 are small spring steel members 42 rigidly secured to the flange by rivets 44. It will thus be evident that to assemble the sub-body on the body it is only necessary to apply the pins 36 to the openings 40 so that the heads 38 will go through the large end and then rotate the sub-housing which will bring the small shank into the elongated slots and where the spring 42 has a depressed section 46 which engages the head 38 to maintain it in the end of the slot and keep the sub-body secured to the body.

The flange 34 on the sub-body carries in a pressed-in groove 35, U-shaped in cross section, a deformable seating gasket 48 which is adapted to press against the inner surface of a lens 50 5 that is supported on the front of the housing by a conventional clamping ring 52 engaging the flanged edge of the body.

Within the hollow portion of the sub-body is suspended a reflector 54 in such a manner that 10 it may be rotated about either a vertical or a horizontal axis for aiming purposes. The specific structure of the suspension will now be set forth. On one side of the horizontal axis of the sub-body 32 is attached a long strap 56 by a 15 rivet 58. Two inturned lugs 60 on the strap engage the walls of the sub-body to assist in the supporting action and to prevent the strap from rotating about the rivet as a pivot. This construction is best shown in Fig. 6. The strap 20 projects forwardly and its extreme portion is made narrower than the main body as at 62 and an elongated opening 64 is provided near its end. This provides two shoulders 66 at the change in 25 section and a spring member 68 having a collar 70, which is adapted to be sprung over the portion 62 and press against the shoulders 66, has two diverging legs 72 which are adapted to press against the inner face of a vertical flange 74 on the edge of the reflector 54. The periphery of 30 the reflector is then bent back upon itself to form a flange 76 in the plane of the axis of the reflector.

The end of the portion 62 extends through an opening 78 in the vertical flange 74 and a retaining lock 80 is adapted to be inserted through 35 the opening 64 and then turned with its reduced mid-section 82 in the slot 64 and pulled back, its shape being such that it will conform to the shape of the reflector flanges and locks the strap to the reflector edge, the springs 72 holding it 40 tightly in place. This will allow the reflector to pivot about this point.

Diametrically opposite the pivotal support just described, there is provided a similar strap 84, the forward portion of which is identical with 45 the strap 56 having a narrower portion 62 projecting through the flange 74 in an opening 78 with a retaining member 80 to prevent the tongue from being withdrawn through the opening and spring legs 72 to press against the inner surface 50 of the flange to keep the retaining member in close contact.

The main body of the strap 84 extends rearwardly through an opening 87 in the sub-body 32 to form portion 86, is then bent at substantially 55 right angles upwardly as at 88 and then forwardly again as at 90, the foremost end of the latter extending back through another opening 89 in the sub-body. The portion 86, which lies parallel to one side of the sub-body, is movably 60 secured thereto by a rivet 92 rigidly secured to the sub-body and extending through a slot 94 in the strap portion 86, the end of the rivet carrying a small disk 96 to prevent the strap from slipping off.

65 A coil helical spring 98 surrounds the portion 90 of the strap behind the sub-body, one end of which presses against the rear face of the sub-body adjacent the opening therein through which the portion 90 projects and the inner face of 70 strap portion 88 and against two lugs 100 pressed from the strap. Therefore the strap 84 may be moved back and forth relative to the sub-frame, the spring tending to keep it to the rear and therefore keep the reflector pulled around on this 75 side. Pressed from the surface of the inner

reinforcing plate 4 is a lug 102 which extends toward the interior of the lamp housing. Near the end of the lug is a flanged opening 104 which supports one end of an adjusting rod 106 the end of which contacts with the rear portion 88 5 of the strap 84 and pushes it back and forth to any desired position.

To the rear of the lug 102 there is an opening 107 in the shell 2 through which extends an angular pressed-out portion 108 of the inner plate 4, the rear wall of which is vertical and has an opening 110 therein through which the opposite end of the rod 106 projects. A sheet metal angular nut locking member 112 is also secured in the opening 110 around the rod and holds nut 114 through which the threaded portion 116 on the rod is applied. On the outside of the portion 108 the rod carries a lock nut 118 and the end of the rod is headed as at 120 and has a slot 20 therein for adjustment.

In order to adjust the reflector 54 about a vertical axis the nut 118 is loosened and the rod 106 rotated in the desired direction which feeds the rod either forward or back to push or allow the strap to move under the influence of spring 25 98 which moves the inner edge of the reflector back or forward. The reflector of course pivots about its connection to the strap 56 diametrically opposite. This gives the horizontal adjustment and, as is evident from the drawings, this adjustment is made from inside the radiator shell and access may be had thereto by raising the hood 25.

In Fig. 1a is shown a slightly modified construction for the strap 84 and spring bias therefor. In this form the strap 84' is secured to the reflector as in the previous case and extends back into the sub-housing 32, its end being bent at right angles to form a lug 85. Rigidly secured in an opening in the lug and with its main axis parallel to the body of the strap 84' is a rod 87. The rod 40 35 87 extends toward the rear and through a long bearing 89 supported in an opening 91 in the sub-housing 32. This long bearing keeps the motion of the rod linear and prevents wobbling upon its forward and rearward motion. Riveted onto 45 the inner end of the rod 87 is a disk 93 against which the rod 106 presses as in the former case. Surrounding the shaft of the rod 87 behind the sub-housing is a helical spring 95 which presses 50 93 to keep the disk in contact with the adjusting rod 106. The operation is, of course, the same as in the previous construction.

In the central part of the reflector is supported a conventional socket 122 for a bulb 124. In the 55 sub-base, to the rear of strap 56, is an opening which has a rubber grommet 126 therein and in the reinforcing plate 4 and the side of the shell is another opening supporting a second grommet 128. The necessary feed wires 130 are carried to 60 the rear of the reflector through these grommets. Two wires are connected to socket 122 for the main headlamp and the other wires are connected to socket 132 supported in the upper part of the reflector and which carries a small bulb 65 134 for parking purposes.

In order to rotate the reflector about a horizontal axis to give the proper vertical adjustment of the beam, the apparatus best shown in Fig. 2 is provided. In the lower portion of the 70 sub-body 32 there is provided a pressed-out portion 136 which is roughly V-shaped. In the two short ends of this portion are a pair of aligned openings 138 and an adjusting screw 140 extends through these two openings and is freely rotat- 75

able therein. The end of the screw extending rearwardly is threaded and near the end is an opening in which a cotter pin 142 is placed to prevent the screw from coming out. An angled spacing member 144, a portion of whose shape conforms to the shape of the outer face of the pressed-out portion 136, is in engagement with the forward portion and then extends at right angles thereto. This spacing member has a pair 5 of aligned spaced openings 146 therein through which the portion of the adjusting screw in front of section 136 extends, the head of the screw engaging the front of the member.

On the body of the threaded portion of the screw is a traveling nut 148 and extending from the nut to the inner face of the pressed-out portion and surrounding the screw is a helical spring 108 whose function it is to keep the head of the screw tightly against the spacing member 10 and assist in feeding the nut along. The under 20 surface of the head contains raised portions to engage serrations in the spacing member 144 to keep a given setting.

Pivotedly connected to the traveling nut 148 is 25 a double strap 152 the ends of which project forwardly and engage the lower periphery of the reflector, one end 154 engaging within the flange 74 and the other 156 around the flange so that the latter is clamped between the two. It 30 will thus be evident that as the screw 140 is rotated, the nut 148 will move in or out and exert a pull or a push on the strap which is transmitted to the reflector rim at the bottom and rotates the reflector about an axis through the strap 35 supports.

In the outer shell of the headlamp 2, opposite the head of the adjusting screw 140, is an opening 158 through which a screw driver or other suitable instrument may be inserted in order to 40 rotate the screw 140 for adjusting purposes. It will thus be evident that the reflector 54 may be adjusted for aiming either about a horizontal or vertical axis without removing any part of the headlamp but by merely utilizing a screw driver to turn either the adjusting screw 140 for rotation about a horizontal axis or by loosening nut 118 and then turning the rod 106 for adjustment about a vertical axis. This latter 45 adjustment is accessible by raising the hood and acquiring access to the inner portion of the 50 radiator shell.

In the modified form shown in Figs. 10-13, inclusive, the main body of the headlamp is formed of a pressed metal portion 160 of a portion 55 of a motor car, such as the fender. In this pressed-out portion there is a vertical circular opening around which the body is flanged as at 162. Carried circumferentially on this flange 162 is a ring member 166 the same being secured thereto by machine screws 168 which project 60 through the ring and the flange to be threaded into a nut 164. In the ring 166 there is a series of circumferentially spaced hollowed-out portions 170 within which there are supported strap 65 springs 172, the outer face of the ring at these points being in the form best shown in Fig. 12, as of irregular outline 174. As in the former instance, there may be any number of these points but the preferable number would be three.

70 A sub-frame member 176 fits within the circular opening in the main body 160 and has a flanged edge portion 178. Within this flanged edge portion there is provided a circumferential groove 180 of U-shaped cross section within 75 which is supported a deformable gasket 182.

The bottom portion of the groove 180 carries a series of headed rivets 184 which are circumferentially spaced to normally lie opposite the hollowed-out portions 170. Therefore in applying the sub-housing to the main body the pins 184 are projected through the slots 174, their heads proceeding into the hollowed-out portion and contacting the springs 172. The whole sub-body is then rotated toward the right as shown in Fig. 12 until the shaft of the pins lies within the small end portion of the slot 174, its head then preventing an axial withdrawal of the sub-body from the main body. This type is known as the bayonet connection. The spring 172 presses against the head to maintain it in its proper position.

Positioned within the central opening in the sub-body is a reflector 186 which has an outwardly and then rearwardly flanged edge 188 which is supported at the two opposite ends of its horizontal axis by a similar construction to that shown in the first form of our invention, the support on one side being identical with that shown in Fig. 1 at the upper portion of the drawing involving the fixed strap 56. The opposite side is supported by an adjustable strap similar to strap 84 shown in Fig. 1 with the exception that in this case the rear portion of the strap 84' extends through an opening in the sub-body and is bent at right angles to itself as at 189 and the upper end thereof is provided with a flanged opening 190 which is internally threaded. Also secured rigidly to the outer surface of the sub-body 176 is an angled member 192 having an opening 194 in axial alignment with the threaded opening 190. The forward portion of the flanged edge and ring members 164 and 166 also have an aligned opening therein for the insertion of an adjusting screw 196, the elongated head of which extends through this last named opening and the smaller body portion extends into opening 194, the threaded end being threaded through the opening 190 and a cotter pin 198 being applied to the innermost end to prevent entire withdrawal of the same. There 45 is also an opening 195 in the base of the groove 180 through which the screw 196 may be inserted or adjusted. Between the two brackets 189 and 192 the shaft of the adjusting screw is encircled by a compressed helical spring 200, the 50 purpose of which is to force the bracket 189 rearwardly and cause the strap 84' to slide upon its rivet 92 which motion is, of course, transmitted to the reflector.

The showing in Fig. 14 is substantially the same as that shown in Fig. 11 in which an adjusting screw 196 has a head thereon projecting through the ring member 166 and is supported in an angled member 192 projected upwardly from the sub-housing 176. As in the former instance the innermost portion of the adjusting screw 196 is of smaller diameter and is threaded for a substantial portion of its length. A strap 84'' is attached to the reflector at its forward portion in the same manner as before, the rearward end of which is bent at an angle as shown at 230 and carries a pin 232 riveted thereto, said pin extending through a bushing 234, said bushing being carried in an opening in the rear face of the sub-housing 176. The projecting portion 60 of the pin 232 has riveted thereto a vertical plate 236 in the upper portion of which is a threaded opening 238 through which the rearward end of the adjusting screw 196 projects. Concentric 65 with the axis of the screw 196 and surrounding 70 75

the portion of smaller diameter between the plate 236 and the angled member 192 is a helical spring 240 which assists when the screw is turned to move the plate 236 back and forth which action is transmitted through the pin 232 to the strap 84''' and thus moves the reflector to its proper position.

In order to provide for the vertical adjustment of the beam in this case, which necessitates rotating the reflector about its horizontal axis, the lower portion of the sub-body is pressed out as before to form a roughly V-shaped section 202, the two end portions of which are provided with aligned openings 204 through which extends a rod 206. Upon the body of this rod, between the two openings, there is secured a nut 208 against one face of which is resiliently pressed a hinge nut 210 by an encircling helical spring 212, the opposite end of which bears against the inner surface of the pressed-out portion 202. Pivotedly secured to this hinge nut 210 is a double strap 152, as in the former case the ends of the strap engaging the flanged edge 188 of the reflector in the same manner as previously described.

The portion of the rod 206 extending rearwardly from the sub-body has an enlarged head 214 having an eye 216 therein in which is adapted to engage one end of a thin angled rod 218 and form pivotal engagement therewith. Secured to the outer face of the sub-body below the pressed-out portion 202 is an angled bracket 220 which is adapted to carry an adjusting screw 222 of the same construction as the adjusting screw 196. The inwardly projecting threaded end of the screw 222 carries thereon a driving nut 224 to which is pivotally secured the opposite end of the thin rod 218. The forward portion of the adjusting screw 222 of course projects through the flanged edge in order to be accessible.

A conventional headlight lens 226 supported by a split rim 228 upon the forward face of the housing engaging the ring 166 in any well known manner, closes the front of the assembly by pressing against the deformable gasket 182. In this form of the invention it is therefore evident that in order to adjust the aiming of the reflector either about a horizontal or vertical axis it is of course necessary to remove the lens and then the two adjusting screws 196 and 222 will be accessible to tilt the reflector by merely turning the same with a screw driver or other similar instrument.

We claim:

1. In a headlamp having a lens and a casing supporting said lens, an adjustable reflector enclosed by the casing for cooperation with the lens, and a pivotal support for the reflector including a forwardly projecting finger extended through an opening in the rim of the reflector, a pin carried by the reflector and loosely engaging an

aperture in said finger and a hairpin spring bearing at its bight on said finger and at its leg extremities on said reflector rim.

2. In a headlamp having a lens and a casing supporting said lens, an adjustable reflector enclosed by the casing for cooperation with the lens, and a pivotal support for the reflector including a pair of fingers projecting at circumferentially spaced points through the rim of the reflector, radial pins on the reflector entering loosely within said fingers and a hairpin spring associated with each finger with its bight bearing on the finger and its legs bearing on the reflector rim.

3. The structure of claim 2 wherein one of said fingers is movable axially of the casing for aiming the reflector.

4. In a headlamp having a lens and a casing supporting said lens, an adjustable reflector enclosed by the casing for cooperation with the lens, and a pivotal support for the reflector including a pair of fingers projecting at circumferentially spaced points through the rim of the reflector, radial pins on the reflector entering loosely within said fingers and a hairpin spring associated with each finger with its bight bearing on the finger and its legs bearing on the reflector rim and adjustable means engaging the reflector in spaced relation to said fingers to swing the same about said pins.

5. In a headlamp having a lens, a lamp casing supporting said lens, a sub-body resiliently mounted in the casing for peripheral sealing engagement with the lens, reflector supporting devices carried by said sub-body, an adjustable reflector pivotally mounted at circumferentially spaced points on said supports for cooperation with said lens, means adjustably mounted on the casing and operable from outside the casing to shift one of said supports in adjusting said reflector and additional means operatively connected with the reflector and accessible from outside the casing to tilt the reflector on said supports.

6. In a headlamp having a lens, a casing supporting the lens, a shiftable member adjustably mounted in and projected through the casing wall, an adjustable reflector for cooperation with said lens, a sub-body having supporting devices engaging the reflector in circumferentially spaced relation to mount the same adjustably therein, one of said reflector supporting devices being shiftable in the sub-body and means mounting the sub-body on the casing in peripheral sealing engagement with the lens and presenting said shiftable reflector supporting device for operative relation to said shiftable casing mounted member.

CLARENCE A. MICHEL.

HOWARD C. MEAD.

ROBERT WINKELMEYER.
